United States Patent

Des. 239,437

Patented Apr. 6, 1976

239,437

OVERCAP FOR A CONTAINER

Stanley W. Boduch, Ludlow, Mass., assignor to Dart Industries Inc., Los Angeles, Calif.

Filed Nov. 7, 1974, Ser. No. 522,084

Term of patent 14 years

Int. Cl. D9—07

U.S. Cl. D9—267

Fig. 1

Fig. 2

Fig. 3

FIG. 1 is a perspective view of an overcap for a container embodying my new design;

FIG. 2 is a side elevational view thereof; and

FIG. 3 is a bottom plan view thereof.

I claim:

The ornamental design for an overcap for a container, substantially as shown.
